UNITED STATES PATENT OFFICE.

EDWARD B. BLAKELY, OF MUSKEGON, MICHIGAN, ASSIGNOR TO GRAY MOTOR COMPANY, OF DETROIT, MICHIGAN, A CORPORATION OF DELAWARE.

BOAT-MOTOR.

1,139,631.

Specification of Letters Patent. Patented May 18, 1915.

Application filed January 9, 1914. Serial No. 811,140.

To all whom it may concern:

Be it known that I, EDWARD B. BLAKELY, a citizen of the United States, residing at Muskegon, in the county of Muskegon and 5 State of Michigan, have invented certain new and useful Improvements in Boat-Motors, of which the following is a specification.

This invention relates to propelling mechanisms adapted to be detachably connected to row boats and other small craft; and it refers particularly to the type that comprises an internal combustion engine connected to drive a propeller and constituting 10 a unitary structure. As heretofore constructed, the engine shaft and the propeller shaft have been connected by means of bevel gears inclosed within a small housing or support. To mount the gears upon their 15 shafts within the housing has been an inconvenient and time-consuming operation. The gears, moreover, are relatively expensive.

One of the objects of this invention is to 20 avoid the trouble and expense incident to the assembling of the gears within the housing, and to substitute a cheaper and equally efficient drive.

In boat motors of the type referred to, the 25 propeller in its rotation exerts a constant tendency to turn the tiller, in consequence of which the steersman is continually obliged to exert strength to counteract such tendency.

It is one of the objects of this invention 30 to overcome the tendency of the propeller to turn the tiller.

A further object is to produce a boat motor which will permit the boat to be steered 35 while the boat is coasting.

In the accompanying drawings Figure 1 40 is a side elevation, partly in section, of a boat motor embodying the features of my invention. Fig. 2 is a fragmental sectional view of the engine shaft and related parts. Fig. 3 is a section on dotted lines 3-3 of Fig. 2. Fig. 4 is a fragmental view of a flexible shaft comprised in the machine.

The engine and its accessories, and the 45 means for securing the engine to a boat, may be of any ordinary or preferred construction, and hence are not illustrated in detail.

1 denotes a bracket of common form by

means of which the motor may be attached 55 to the stern of a boat.

2 indicates an engine, the frame of which may have an adjustable connection with bracket 1, as usual.

3 is the engine crank shaft.

4 is a vertical bearing sleeve which is rigid with the engine frame. A tiller 5 is rigidly secured to a sleeve 6 which is rotatably mounted upon the bearing sleeve 4, the lower end of the sleeve 6 being vertically 65 slotted.

The means for connecting the engine shaft 3 to the propeller is inclosed within a rigid tube 7, the upper portion of which is straight and extends within the tiller sleeve 6. The 70 tube 7 is adjustably clamped in the sleeve 6 by means of a bolt 8 which serves to draw the slotted portion of the sleeve 6 into clamping contact with the tube. The lower portion of the tube 7 is curved rearwardly. To 75 its lower, rear end is fixed a bearing sleeve 9. The connection between the tube 7 and the sleeve 9 may be of any suitable character, preferably such as will permit said parts to be conveniently separated when necessary. 80 The sleeve 9 may have a driving fit in the tube 7. In the sleeve 9 is rotatably supported the propeller shaft 10 having a propeller 11 mounted on its rear end.

The connection between the engine shaft 85 3 and the propeller shaft 10 consists of a rigid shaft section 12 and a flexible shaft section 13. The upper end of the shaft section 12 is tubular and fits slidably over the lower end of the engine shaft 3. The shafts 90 3 and 12 may be connected in any suitable way so as to rotate together; herein I have shown a key 14 carried by the shaft 12 and fitting within a longitudinal keyway 15 in the shaft 3. The flexible shaft section 13 95 is connected at its upper end to the lower end of the shaft section 12 by means of a screw or equivalent member 16; and is connected at its lower end to the forward end of the propeller shaft by a screw 17 or the 100 like.

To protect the tube 7 from wear due to contact with the flexible shaft section 13, suitable means may, if desired, be provided, such as a coiled spring 18 fitting within the 105 curved portion of the tube and loosely surrounding the shaft-section 13. A pump 19 may, if desired, be attached to the sleeve 9,

the plunger 20 of the pump being operated by an eccentric portion 10^a of the shaft 10 and by a spring 21. The pump discharges into a tube 22 which is connected through a flexible tube (not shown) with the water jacket of the engine. Within the curve formed by the tube 7 is secured a rudder plate 23, said plate being suitably attached to the tube and to the pump 19. The plate 23 is located between the axis of the tiller and the vertical plane of the propeller.

The engine 2 and the tube 7 may be secured in an adjusted position with reference to the bracket 1 by any suitable means, a portion of a means ordinarily used for this purpose being shown at 24. The tube 7 being vertically adjustable with relation to the tiller sleeve 6, and the shaft-section 12 being vertically adjustable with reference to the engine shaft 3, it will be seen that the propeller 11 may be raised or lowered to meet practical requirements. The tube 7 may be filled with lubricant in order to insure the proper lubrication of the flexible shaft-section 13 and the propeller shaft 10. When it is desirable to renew the supply of lubricant in the tube 7, or to replace the coiled spring 18, the bolt 8 is loosened, the tube 7 withdrawn from the sleeve 6, and the sleeve 9 withdrawn from the tube 7, the separation of the parts 7 and 9 bringing the screw 17 into position where it can be removed. Upon the removal of the screw 17, the shaft sections 12 and 13 may be withdrawn from the upper end of the tube 7.

It will be apparent that the parts forming the driving connections between the engine and the propeller may be easily and quickly assembled and dismembered.

In operation, the tendency of the boat to veer to one side, owing to the action of the propeller, is almost entirely overcome partly by the provision of the rudder plate 23, and partially by reason of the considerable distance between the axis of the tiller and the vertical plane of the propeller. When the boat is coasting, the rudder plate 23 enables the boat to be steered. Said plate also serves to stiffen the curved portion of the tube 7.

I claim as my invention:

1. In a boat motor, a motor, a vertical shaft driven by the motor, a propeller shaft extending at an angle to the vertical shaft,

flexible shafting connecting said shafts, means inclosing said flexible shafting, a removable wear-receiving lining for said inclosing means, and a propeller on the propeller shaft. 55

2. In a boat motor, a motor, a vertical shaft driven by the motor, a propeller shaft 60 extending at an angle to the vertical shaft, flexible shafting connecting said shafts, means inclosing said flexible shafting, a coiled spring surrounding the flexible shafting within the inclosing means, said spring 65 constituting a wear-receiving lining for the inclosing means and being free from connection with the shafting, and a propeller on the propeller shaft.

3. In a boat motor, a motor, a vertical shaft-section driven by the motor, a rigid tube having a straight upper portion inclosing said shaft-section and a rearwardly curved lower portion, a bearing sleeve detachably connected to the rear end of the 75 tube, a propeller shaft mounted in the bearing sleeve, a flexible shaft-section in the curved portion of the tube, the upper end of said flexible shaft-section being connected to the lower end of the vertical shaft-section, a detachable connection between the rear end of the flexible shaft-section and the forward end of the propeller shaft, said detachable connection being rendered accessible when the bearing sleeve is detached from 80 the tube, and a propeller on the propeller shaft. 85

4. In a boat motor, a motor, a rigid tube having a straight upper portion and a rearwardly curved lower portion, a bearing 90 sleeve the forward end of which is connected to the rear end of said tube, a propeller shaft mounted in the bearing sleeve, the forward end of said propeller shaft extending forwardly of the forward end of 95 the sleeve, shafting driven by the motor and inclosed within said tube, said shafting being detachably connected to the forward end of the propeller shaft, and a propeller on the propeller shaft. 100

In testimony whereof I affix my signature in presence of two witnesses.

EDWARD B. BLAKELY.
